UNITED STATES PATENT OFFICE.

JOHN J. BOAX, OF MCKEESPORT, AND BORIS S. ROBINOFF, OF PITTSBURGH, PENNSYLVANIA, ASSIGNEES TO NATIONAL TUBE COMPANY, OF PITTSBURGH, PENNSYLVANIA, A CORPORATION OF NEW JERSEY.

RADIAL MULTIPLE-SPINDLE DRILL.

Application filed December 12, 1922. Serial No. 606,464.

This invention relates to drilling machines and more particularly to a radial multiple spindle drilling machine, and while not limited thereto, is particularly adapted for drilling the ends of pipe in the making of bump joints.

The primary object of the invention is to provide a machine of this class which is provided with a plurality of drill heads adapted to be independently adjusted at various angles radially around the work and also at various angles to the vertical axis of the work, so that the center lines of drills carried by the head, when extended, will meet.

Another object is to provide a machine of this class having novel operating connections which will permit the various adjustments of the drill heads to be made without disassembling any of such connections.

A still further object is the provision of a machine of this class having the novel features, construction, and combination of parts described in the following specification and illustrated in the accompanying drawings.

In the drawings, Figure 1 is a side elevation of a machine constructed in accordance with the invention.

Figure 2 is a plan view thereof partly in section.

Figure 3 is a sectional elevation showing the interior of the drive housing.

Figure 4 is an enlarged top plan of one of the drill heads.

Figure 5 is a typical longitudinal sectional elevation taken through the drill head of Figure 4.

Figure 6 is a sectional elevation taken on the line VI—VI of Figure 5.

Figure 7 is a similar view on the line VII—VII of Figure 5.

Figure 8 is an enlarged sectional plan through the drive housing showing the motor drive connections.

Figure 9 is an enlarged typical sectional plan through the drive housing.

Figure 10 is an enlarged typical sectional elevation through the drive housing.

Referring more particularly to the drawings, the numeral 2 designates the base on which is mounted a vertical drill head support 3 and drive housing 4.

The support 3 is provided with an arcuate shaped guide plate portion 5 on which a plu-

rality of drill heads 6 are slidably mounted. The drill heads 6 comprise a base portion 55 7 having upstanding ears 8 and 9. A spindle carrier 10 is pivotally mounted at 11 to the forward ears 8 and is adjustably mounted between the ears 9 by a bolt 12 which passes through suitable arcuate slots 13 in the ears 9 and through an aperture in said carrier, the bolt being adapted to be screwed up against the ears 9 to lock the carrier in position with relation to said ears. A sleeve member 14 is slidably mounted 60 within the spindle carrier 10 and is provided with a longitudinally extending rack portion 15. A vertically disposed stub shaft member 16 is journaled in the carrier 10 and has its lower end provided with teeth forming a pinion portion 17 which is in mesh with the rack portion 15 of the sleeve 14. A worm wheel 18 is loosely mounted adjacent the upper end of the shaft 16 and is adapted 65 to be engaged by a clutch member 19 mounted on the upper end of the shaft 16 and adapted to be locked in operative position by thumb-nut 20. A feed shaft 21 is journaled in suitable bearings 22 and 23 in the carrier 10 and is provided with a worm 70 24 which is in mesh with the worm wheel 18. It will be readily seen therefore that when the shaft 21 is rotated, if the clutch 19 is in operative position, shaft 16 will be rotated through the worm 24 and worm wheel 18, 85 and that the pinion portion 17 of the shaft 16 will travel along the rack 15 of the sleeve 14, thus feeding the sleeve forward or backward according to the direction of rotation.

A drill spindle 26 is revolvably mounted 90 within the sleeve 14 and locked against longitudinal movement relative thereto so as to be compelled to move therewith. The forward end of the spindle 26 is provided with a tapered recess 27 for the reception of a drill. A pinion 28 is slidably mounted on the extended portion 29 of spindle 26 which projects rearwardly from the sleeve 14. A stub-drive shaft 30 is journaled in the enlarged portion 31 of the spindle carrier and carries a pinion 32 which meshes with the pinion 28 on the spindle 26, and is adapted 95 to rotate said spindle. The base portion 7 of each drill head 6 is provided with flanges 33 adapted to contact with the side edges of the guide plate portion 5 of the support 3 100 105 110 115 120 125 130 135 140 145 150 155 and retaining plates 34 are detachably secured to said flanges by bolts 35, and project inwardly over said guide plate portion 5 of the support so as to prevent displacement of the drill heads. It will readily be seen that by loosening the bolts 35 the heads may be freely adjusted along the plate 5, and by tightening the bolts the heads may be locked in position.

10 The guide plate 5 of the drill head support 3 is cut away to form a centrally arranged recess or slot 36 and shoulders 37-38. Racks 39 and 40 are mounted on the shoulders 37-38, respectively. A stud member 15 41 is mounted in a suitable aperture in the base portion 7 of the drill heads and is provided with an enlarged bearing portion 42 terminating at its upper end in a shoulder portion 43 adapted to bear against the under 20 side of the base 7, and the lower end of said enlarged portion 42 terminates in a flange 44. The upper end of the stud member 41 is provided with lock nuts 45 adapted to lock the stud against vertical movement.

25 A pinion 46 is mounted on the portion 42 of the stud and is supported by the flange 44, and is cut away to form a shoulder 47 for the support of a ring pinion 48 which is secured thereto by pins 49. The ring pinion 30 48 is in mesh with the rack 39.

35 A second stud 51 is mounted in an aperture in the base portion 7 of the drill heads forward of the stud 41 and carries a pinion 50 which is in mesh with the pinion 46 and the second rack 40.

When it is desired to move the drill heads 6 along the guide plate 5 of the drill head support, the stud 41 is rotated. Rotation of the stud 41 will rotate the pinions 46, 48, 40 and 50, and the pinions 48 and 50 will travel along the racks 39 and 40, thereby moving the heads.

The drive housing 4 has a main drive shaft 52 and main feed shaft 53 journaled therein. 45 The main drive shaft 52 is adapted to receive its power from a motor 54 mounted on a motor stand 55 and connected by a flexible coupling 56 to a stub shaft 57 journaled in bearing 58 secured in the housing 4, and provided with a beveled gear 59 which meshes with a beveled gear 60 on the drive shaft 52.

The main feed shaft 53 receives its power from a motor 61 mounted on a motor stand 62 and connected by a flexible coupling 63 to a stub shaft 64 journaled in bearing 65 secured in the housing 4, and provided with a worm 66 which meshes with a worm wheel 67 on the feed shaft 53.

A plurality of sub-drive shafts 68 corresponding in number to the number of drill heads 6 are positioned in the housing 4 at right angles to the main drive shaft 52, and are journaled in suitable bearings 69 in the housing, and are provided intermediate their 60 ends with a spiral toothed gear 70 which is

meshed with a second spiral toothed gear 71 on the main drive shaft 52. The forward end of each of the sub-drive shafts 68 projects through the forward wall of the drive housing and is connected to a two-part telescoping shaft 73 by a universal coupling 74. The shafts 73 have their forward ends connected to the drive shafts 30 journaled in the drill heads by universal couplings 75. Therefore, power from the main drive shaft 75 is communicated to the shaft 30 and thence through pinion gears 32 and 28 to the spindle 26.

The lower end of the drive shaft 52 is connected by gears 76 with an oil pump 77 adapted to force oil throughout the housing 4.

A plurality of sub-feed shafts 78 corresponding in number to the number of drill heads 6, are positioned in the housing 4 at right angles to the main feed shaft 53 and are journaled in suitable bearings 79 in the housing, and are provided intermediate their ends with a spiral toothed gear 80 which is meshed with a second spiral toothed gear 81 on the main feed shaft 53. The forward end of each of the sub-feed shafts 78 projects through the forward wall of the drive housing and is connected to a two-part telescoping shaft 83 by a universal coupling 84.

The shafts 83 have their forward ends connected to the feed shaft 21 in the carrier 10 by universal couplings 85. Therefore, power from the main feed shaft is communicated to the shaft 21 and thence through the worm 24 and worm wheel 18 to the shaft 16 and pinion 17 to feed the sleeve 14 and spindle 26 forward or backward relative to the drill heads.

The above described machine is primarily designed for drilling rivet receiving apertures in the periphery of bump joints of large diameter pipe. Therefore, assuming that such an operation is to be performed, the operation of the machine will be as follows—

The drill heads 6 will be adjustd along the guide plate 5 of the support 4 in order to position them radially around the work, and then the spindle carriers 10 will be adjusted around the pivot 11 in order to position the drills on the proper angle. It will be noted that due to the universal connections of the shafts 73 and 83, and the fact that these shafts are extensible, the heads 6 are free to be adjusted without interfering with their drive connections.

After the proper adjustments are made, the motors 54 and 61 are operated to furnish power to the main drive shaft 52 and main feed shaft 53. The several sub-drive shafts 68 and sub-feed shafts 78 being geared to the main drive and feed shafts, respectively, will all be operated simultaneously, and due to their positive connections with the shafts 130

30 and 21 in the drill heads will cause a simultaneous drive and feed of the drill spindle 26.

When it is desired for any reason to prevent the drill spindle in any one of the heads 6 from being fed into the work, the clutch member 19 may be rendered inoperative by loosening the thumb-nut 20, thus permitting said clutch member to move away from and 10 out of engagement with the worm wheel 18 and thereby causing said wheel to rotate freely on the shaft 16.

While we have described and illustrated only one embodiment of our invention, it will be understood that we do not wish to be limited to the exact constructions illustrated, since various modifications may be made in design, construction, and combination of parts without departing from the scope of 20 this invention as defined in the appended claims.

We claim—

1. A radial multiple spindle drilling machine, comprising an upright drill-head support provided with an upright arcuate guideway, an upright series of drill-heads mounted on said guideway and adjustable along said guideway relative to each other, drill spindles mounted for rotation on said 25 drill-heads, in combination with an upright housing separate from and in rear of said support, an upright main drive shaft in said housing, an upright series of substantially horizontal sub-drive shafts in said housing 30 and geared to said main drive shaft, and drill driving means including longitudinally expandible shafts for connecting the said drill driving means and also including means to permit individual adjustment of the 35 drill-heads along the arcuate guideway without interfering with the drill driving 40 means.

2. A radial multiple spindle drilling machine, comprising an upright drill-head support provided with an upright arcuate guideway, an upright series of drill-heads mounted on said guideway and adjustable along said guideway relative to each other, drill spindles mounted for endwise feed and 45 rotary drive movements on said drill-heads, in combination with an upright housing separate from and in rear of said support, an upright main feed shaft in said housing, a motor geared to said feed shaft, an upright 50 series of substantially horizontal sub-feed shafts in said housing and geared to said main feed shaft, and drill feeding means in-

cluding longitudinally expandible shafts for connecting the sub-feed shafts with the respective drill spindles to feed the latter endwise, said drill feeding means also including means to permit arcuate adjustment of the drill-heads without interfering with the 60 drill-feeding means.

3. A radial multiple spindle drilling machine, comprising an upright drill-head support provided with an upright arcuate guideway, an upright series of drill-heads mounted on said guideway and adjustable along said guideway relative to each other, 65 sleeve members mounted on said heads and movable endwise thereon, drill spindles revolvably mounted in said sleeve members to move longitudinally therewith, a rack on each of said sleeve members, pinions mounted on the drill-heads and in mesh with the racks to move said sleeve members endwise, an upright housing separate from and in rear of the support, an upright feed shaft within 70 the housing, a motor geared to said feed shaft, an upright series of substantially horizontal sub-feed shafts in said housing and geared to the main feed shaft, drill feeding means extending between the sub-feed shafts and the respective pinions including longitudinally expandible shafts and universal joints to permit arcuate adjustment 75 of the drill-heads without interfering with the drill feeding means.

4. A radial multiple spindle drilling machine, comprising an upright drill-head support provided with an upright arcuate guideway, an upright series of drill-heads mounted on said guideway and adjustable along said guideway relative to each other, 80 a spindle carrier mounted on each of said drill-heads and pivotally adjustable in a plane at right angles to that of the arcuate guideway, a sleeve member mounted on each of said spindle carriers and movable endwise thereon, drill spindles revolvably mounted in said sleeve members and movable therewith, feeding means for feeding the sleeves and spindles to and from the work, and driving means for rotatably operating 85 the said spindles, the feeding means and the driving means each including means to permit adjustment of the drill-heads and the spindle carriers without interfering with the feeding means and the driven means. 90

In testimony whereof we have hereunto signed our names.

JOHN J. BOAX.
BORIS S. ROBINOFF.
